FORE-AND-AFT SAIL SETTING AND MAGAZINE CONSTRUCTION

Stephen Enke, New Haven, Conn.

(Economics & Business, Duke University, Durham, N.C.)

Filed Mar. 28, 1960, Ser. No. 17,860

9 Claims. (Cl. 114—102)

This invention relates to an adapter mounting for a fore-and-aft sail of the type known as a staysail, that permits the sail to be quickly and easily set on or removed from the standing rigging of a sailboat or vessel. It is particularly adapted for use with the usual forward jib stay of a sailboat of any size and especially for sailboats having crews limited in number and where rough weather conditions are encountered that require frequent setting on, removal and stowage of the staysail by reason of the rapidity and relative ease with which it permits these operations to be effected.

Accordingly, it is an object of the invention to provide an adapter arrangement, for a staysail or the like, which not only constitutes a flexible sail-positioning and sail stowage unit, enabling the stowage in the usual flexible shipboard manner but also in addition provides for setting the sail on and removing it from the stay in a simple, fast, and relatively effortless manner.

Another object is the provision of a sail setting-and-stowage flexible cable magazine unit from which and onto which the sail can easily and quickly be directly slid when setting the sail or stowing it.

Another object is the provision of a sail setting-and-stowage flexible cable magazine from which and onto which a fore-and-aft plural slider-mounted sail can be directly slid with the slide fasteners automatically maintaining proper alignment with each other.

Another object is to provide a staysail magazine unit that functions as a means for locked stowage of the sail thereon and also to lockingly retain the sail on the boat stay after being set thereon from the magazine.

Another object is to provide a sail mounting and magazine adapter arrangement that is of simple construction, low in manufacturing costs, light in weight enabling it to be easily handled, and sufficiently strong to withstand rough handling without damage.

The foregoing and other objects of the invention will be understood from the following description which, taken in connection with the accompanying drawings, disclose a preferred embodiment thereof.

Referring to the drawings:

FIGURE 1 is a side elevation of the staysail adapter mounting and stowage magazine shown in operative relation to the lower deck-anchored end of the boat or mast stay with the sail disposed partly on both the stowage magazine and boat stay;

FIGURE 2 is a vertical sectional view of the sail mounting and stowage magazine;

FIGURE 3 is a side elevational view, partly in section, of the stay adapter fitting component; and

FIGURE 4 is a sectional view, taken on line 4—4 of FIGURE 1.

As illustrated, the construction includes a boat stay adapter fitting 10 of suitably strong and non-rusting metal, such as stainless steel, that is of dumbbell cross section, noting FIGURE 4. Both end portions 11 and 12 thereof are preferably of corresponding circular or cylindrical section and integrally connected together by means of a waist or web section 13. End portion 11 is preferably of greater length than portion 12 and at each of its ends is provided with an eye 14. Portion 12 of the adapter fitting 10, which is coextensive with the upper end of portion 11, is provided with a suitable and conventional stay

2

receiving and connector structure, here shown as an anchoring socket 19 into which the lower end of the boat stay 20, comprising a part of the standing rigging, is securely attached. The lower end of the end portion 12 terminates in a threaded male stud 21 for a purpose to be hereinafter explained. A suitable deck anchoring means 25, including a conventional turnbuckle or the like 26 is connected to lower eye 14 of the adapter fitting by means of a suitable pin means 27.

10 The sail setting adapter and magazine stowage unit, generally designated 29, comprises a flexible cable 30 of suitable length and which may be of non-rusting metal strands or synthetic fiber. Rigidly attached to one end of flexible cable 30 by conventional attaching means is 15 a metallic end member 31 having a rotatable connector element 32 having an axially aligned threaded socket 33 which is threadably engageable with the complementary threaded stud 21 on the adapter fitting 10. The exterior of connector element 32 is suitably knurled at 34 for 20 facilitating manual attachment thereof. At the opposite end of cable 30 fixedly attached thereto, by conventional attaching means, is a metallic end member of enlarged diameter having formed laterally thereon an enclosure or clip device 36 the opening 37 of which is normally maintained closed by a spring-urged closure gate member 38. At its outer free end the end member is provided with 25 an axially aligned threaded stud 40 identical with threaded stud 21 on adapter fitting 10 in size and number of threads.

30 The diameters of the stay cable 20 and magazine cable 30 are substantially the same while the diameters of the cable end member 31 and connector element 32 are of the same size as that of each of the portions 11 and 12 of adapter fitting 10 which are of a diameter as closely 35 approaching the diameter of the cables 20 and 30 as is permissible for retention of structural stability and requisite strength. Likewise, the dimensions of the space within the clip device 36 and the width of the normally closed opening 37 thereto are such as will freely receive 40 stay 20 when the device 36 is clipped thereon.

The luff or leading edge 51 of the fore-and-aft sail 50 has secured thereto, as by stitching or the like, appropriately spaced suitable metallic stay-attaching slide fasteners or hanks 52. These slide fasteners, as shown in

45 FIGURE 4, each comprise two complementary arcuate arms 53 and 54, the free ends of which are spaced apart a distance sufficient to slide freely over adapter fitting web 13 but sufficiently close together to retain the slide fasteners on either stay 20 or magazine cable 30 though 50 freely slidable thereon. The diameter of end member 35 is sufficiently large to prevent passage of the sliders 52 thereover.

To use the disclosed construction, the boat rigging is 55 first modified to the extent, as shown in FIGURE 1, of slightly shortening the lower end of the rigging line or stay 20 and attaching the stay adapter fitting 10 thereto at 19. The conventional stay deck anchorage and tightening means 25, 26 is then coupled to the adapter unit by means of the coupling pin 27 or the like.

60 To set or mount sail 50 on stay 20 the flexible magazine unit 29, with the sail slide fasteners 52 engaged with its cable 30 and locked thereon by means of the socket connector 32 at one end of the cable, being threadedly engaged with stud 40 at the other end to in effect form an endless cable loop, is placed on the deck in proximity to the anchored end 25 of the stay structure (FIGURE 1). The threaded end socket 32 of the sail magazine is then manually unscrewed from stud 40 at the opposite end of the magazine and threadedly attached to the stud 21 of the adapter fitting 10. The sail 50 is then raised or set into proper position on the

70

stay by means of a conventional halliard (not shown) attached to the sail. During this maneuver the slide fasteners 52 freely slide, one after the other automatically in proper alignment from magazine cable 30, over its end elements 31, 34 and over portion 12 of the adapter fitting 10 onto the stay cable 20. After the sail is completely withdrawn from the magazine unit 29 onto the stay 20 the magazine clip device 36 of the magazine cable end member 35 is then clipped onto the stay above the fitting 10. Since the clip device prevents the magazine end member 35 from sliding down over the adapter fitting 10 by reason of the fitting web 13 the sail is locked onto the stay as long as the clip structure 36 remains in its clipped position thereon.

To stow or remove the sail from the rigging line or stay 20, clip device 36 is removed from stay 20 and placed on the boat deck, as indicated in FIGURE 1. As sail 50 is lowered the sail slide fasteners 52 merely slide down the stay onto and over portion 12 of fitting 10 and thence onto sail magazine cable 30 whereby the lowermost slider 52 will abut against the magazine end member 35. When all of the sail slide fasteners 52 have been slid onto magazine cable 30 the sail halliard is detached and the threaded magazine end connector socket 32 is unscrewed from the adapter fitting stud 21 and again threadedly attached to stud 40 at the opposite end of the magazine. The magazine, with the sail mounted therein, is then ready for removal to storage.

It will be obvious to those skilled in the art that various changes may be made in the invention without departing from the spirit and scope thereof and therefore the invention is not intended to be limited by that which is shown in the drawings and described in the specification, but only as indicated in the appended claims.

I claim:

1. A sail stowage and setting construction for setting on or removal of a sail from a rigging line of a vessel, comprising a rigging line including an adapter fitting having an end connector thereon in alignment with the rigging line, a flexible cable means having complementary connector means at each end thereof, said end connector means being releasably engageable with each other to form an endless loop sail magazine, one of said cable end connector means being releasably engageable with said adapter fitting end connector whereby the sail may be slidably moved from the rigging line onto the flexible cable magazine and vice versa.

2. A sail stowage and setting construction for setting on or removal of a sail from a rigging line of a vessel, comprising a rigging line including an adapter fitting having an end connector thereon in alignment with the rigging line, a flexible cable having complementary connector means at each end thereof, said end connector means being releasably connectable with each other to form an endless flexible loop sail magazine, one of said cable end connector means having a clip device thereon, the other of said cable end connector means being releasably connectable with said adapter fitting end connector whereby the sail may be slidably moved from the magazine cable onto the rigging line or vice versa, said clip device on said one end cable connector means being releasably engageable with said rigging line above said adapter fitting to prevent return of the sail to the flexible cable magazine.

3. A sail stowage and setting construction for setting on or removal of a sail from a rigging line of a vessel comprising a sail, a rigging line, and rigging line engageable slider mounting means specially secured along the luff of the sail, said rigging line including an adapter fitting having an end connector thereon in alignment with the rigging line, a flexible cable means having complementary connector means at each end thereof, said connector means being releasably engageable with each

other to form an endless loop sail magazine, one of said cable end connectors being releasably connectable with said adapter fitting end connector and said sail mounting slider means being freely slidable on said cable end connector means and said adapter fitting whereby said sail may be slidably moved from the flexible cable magazine onto the rigging line or vice versa.

4. The sail stowage and setting construction defined in claim 3 wherein the other of said cable end connectors 10 includes a rigging clip device thereon, said rigging clip device having a spring-closed closure to releasably retain the clip device in engagement with said rigging line to prevent said sail slider mounting means from moving from said rigging line to said magazine cable when the 15 sail is set.

5. A flexible magazine for use in stowing or setting a fore-and-aft type sail on a rigging line of a vessel, comprising a flexible cable of a length to receive all the slider mounting means of a given sail thereon, a rigid member 20 secured to each end of said cable, one of said cable rigid end members including a rotatable threaded female connector device thereon in alignment with the longitudinal axis of said cable, the other of said cable rigid end members including a complementary male threaded stud 25 thereon in alignment with the longitudinal axis of said flexible cable and said rotatable female connector device, said two end connector devices being releasably secured together whereby the sail is adapted to be securely retained on said flexible cable.

6. A flexible magazine for a fore-and-aft sail as defined in claim 5 wherein said other of said cable rigid end members has a rigging line clip device formed at the side thereof, spring-urged closure means normally maintaining said rigging line clip device closed.

7. A rigging line adapter fitting unit for attachment thereto of a flexible cable magazine adapted to contain a fore-and-aft sail for mounting on a ship's rigging line by means of sliders spacially secured to the edge of the sail, comprising a rigid elongated member, said member 40 including two substantially cylindrical portions integrally connected together by a web of reduced thickness, a rigging line connector means mounted at one end of one of said cylindrical members and a threaded stud at its opposite end, said threaded stud and said rigging line connector means both extending in alignment with the longitudinal axis of said one cylindrical member, the other of said cylindrical members having an anchorage attaching eye on at least one of its ends.

8. A flexible sail magazine, adapted for connection to the end of a rigging line of a vessel, comprising a flexible cable of a length and diameter adapted to slidably receive all of the slider mounting means of a fore-and-aft type sail thereon, a relatively rigid end structure secured to said flexible cable at each end thereof, a threaded rotatable coupling member on the said end structure at one end of said flexible cable, a complementary threaded coupling member on the end structure at the opposite end of said flexible cable, said coupling members being 55 interengageable to form an endless flexible sail magazine.

9. A flexible sail magazine as defined in claim 8 wherein the end structure on said opposite end of said flexible cable has mounted thereon a spring-closed clip device for clipping onto the rigging line and adapted 60 when so connected to constitute an abutment means for the sail slider mounting means.
